Primary Examiner — Rebecca Tsehay

(57) CLAIM

The ornamental design for a combined smoking article and hand-held holder, as shown and described.

DESCRIPTION

FIG. 1 is a top elevational perspective view thereof combined smoking article and hand-held holder;

FIG. 2 is a plane view thereof;

FIG. 3 is another top view thereof; and,

FIG. 4 is a left side view thereof.

The broken lines in the drawing depict portions of the combined smoking article and hand-held holder, that form no part of the claimed design.
